(57) **CLAIM**

The ornamental design for a travel coffee kit as shown and described.

DESCRIPTION

FIG. 1 is a top perspective view of the travel coffee kit of the present invention;

FIG. 2 is a bottom perspective view of the travel coffee kit of the present invention;

FIG. 3 is a front elevation view of the travel coffee kit of the present invention;

FIG. 4 is a rear elevation view of the travel coffee kit of the present invention;

FIG. 5 is a first side elevation view of the travel coffee kit of the present invention;

FIG. 6 is a second side elevation view of the travel coffee kit of the present invention;

FIG. 7 is a top plan view of the travel coffee kit of the present invention; and,

FIG. 8 is a bottom plan view of the travel coffee kit of the present invention.

1 Claim, 4 Drawing Sheets
